TOY TOWER FOR SIMULATED FLIGHT CONTROL

Robert B. Lovejoy, Hermosa Beach, Bruce Ashby, Torrance, Denis V. Bosley, Palos Verdes Peninsula, and Raymond J. Douglas, Lomita, Calif., assignors to Mattel, Inc., Hawthorne, Calif.

Filed Apr. 2, 1971, Ser. No. 130,860

Term of patent 14 years

Int. Cl. D21—01

U.S. Cl. D34—15

Fig. 1

Fig. 2

Fig. 3

FIG. 4

FIG. 5

FIG. 6

FIG. 7

FIG. 1 is a perspective view of a toy tower for simulated flight control embodying our design;
FIG. 2 is a left-side elevational view of same;
FIG. 3 is a front elevational view thereof;
FIG. 4 is a rear elevational view thereof;
FIG. 5 is a right-side elevational view of same;
FIG. 6 is a top plan view thereof; and
FIG. 7 is a bottom plan view.

We claim:

The ornamental design for a toy tower for simulated flight control, as shown and described.
